Attorney

UNITED STATES PATENT OFFICE.

THOMAS H. EUBANKS, OF MEXIA, TEXAS.

PITMAN RING.

Application filed November 9, 1926. Serial No. 147,287.

This invention relates to pitman rings and more particularly to a device of this character for maintaining the pitmen of well drilling apparatus in position upon the wrist pins 5 thereof.

An important object of the invention is to provide a device of this character which may be readily applied and removed and when applied will very firmly lock the pitman upon 10 the wrist pin and which is capable of being very readily removed, when desired.

A further object of the invention is to provide a device of this character which may be readily and cheaply manufactured, which 15 will be durable and efficient in service and a general improvement in the art.

These and other objects I attain by the construction shown in the accompanying drawing, wherein for the purpose of illustration 20 is shown a preferred embodiment of my invention and wherein:

Figure 1 is a side elevation showing a pitman ring constructed in accordance with my invention applied to the crank pin of well 25 drilling apparatus;

Figure 2 is a front elevation partially in section of the ring unapplied;

Figure 3 is a section on the line 3—3 of Figure 2;

Figure 4 is an inside elevation of the fragment of the ring showing the recess within which the pin is located;

Figure 5 is a fragmentary elevation of the ring at the opening provided for the pin.

Referring now more particularly to the drawings, the numeral 10 indicates a ring or collar adapted for engagement with the wrist pin and having a central opening 11 in which the wrist pin fits neatly. This ring is provided with diametrically extending aligned bores 12 and 13. The bore 13 has its outer end counterbored, as indicated at 14, and its inner end in communication with a recess 15 formed in the inner face of the ring. The bores 12 and 13 provide a mounting for the ends of a pin 16, one end of which has a head 17. Adjacent this head, the pin 16 has projecting from the side face a lug 18, this lug being spaced from the adjacent face of the head a distance slightly greater than the distance between the outer face of the ring 10 and the adjacent wall of the recess 15. The wall of the bore 13 and of its enlargement 14 are formed with a channel 19 permitting the pas-

sage of this lug from the outer face of the ring 10 to the recess 15. When positioned within the recess 15, the pin 16 may be rotated to align this lug with a socket formed in the face of the wall of the recess or socket 20 for its reception. Between the head 14 and the base of the counterbore, a spring 21 surrounds the pin and acts to constantly urge the pin outwardly, so that this pin will be held in the recess 20 and may only be aligned with the channel 19 by forcibly shifting the pin 16 longitudinally and rotating the same while shifted inwardly.

It will be obvious that with this pin passed through a bore 22 formed in the wrist pin 23 for its reception, the collar 10 and accordingly a pitman 24 retained in position by the collar will be firmly held against longitudinal movement upon the wrist pin.

Since the construction hereinbefore set forth is capable of a certain range of change and modification without materially departing from the spirit of the invention, I do not limit myself to such specific structure except as hereinafter claimed.

I claim:

In combination with a wrist pin having a pin receiving bore, a collar applied thereto and having diametrically opposed bores aligned with the bore of the wrist pin, a locking pin extending through the bores of the collar and engaged in the bore of the wrist pin, the collar at the inner end of one of the bores thereof having a recess enlarging the bore, there being a socket at the inner end of said recess, the collar at the outer end of said bore having a further recess, the wall of said bore having a longitudinal channel circumferentially spaced from the socket at the inner end of the first named recess, the locking pin having a lug passable through said channel for engagement in the first named recess and alignable with the socket by rotation of the locking pin said lug being disposed in said socket, the outer end of the locking pin having a head, and a spring surrounding the locking pin between the lug and head and seated in the last named recess and constantly urging the head of the locking pin outwardly.

In testimony whereof I hereunto affix my 105 signature.

THOMAS H. EUBANKS.
